UNITED STATES PATENT OFFICE

FRANK F. SCHMANSKA, OF BURLINGTON, VERMONT

FEELER

Application filed September 20, 1930. Serial No. 483,314.

This invention relates to a feeler for looms, the general object of the invention being to provide means which will eliminate a plurality of parts from the multiple wire filling detector made by the Crompton & Knowles Loom Works, of Worcester, Mass., thereby reducing the cost of the loom and the repair cost, increasing production and reducing labor. The loom will operate a bobbin which is not provided with holes and hold the abrasive hooks to make the change from an empty bobbin to a full bobbin in one operation.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a top plan view of a feeler made in accordance with this invention.

Figure 2 is a similar view, but with the detector moved along an empty bobbin.

Figure 3 is a side elevation.

Figure 4 is a detail view showing how the adjusting screw at the tail end of the detector pushes one abrasive hook into engagement with the other hook.

Figure 5 is a view of the body and cap part of the device separated.

Figure 6 is a section on line 6—6 of Figure 5.

Figure 7 is a section on line 7—7 of Figure 5.

Figure 8 is a section on line 8—8 of Figure 5.

Figure 9 is a section on line 9—9 of Figure 5.

In these drawings, the numeral 1 indicates the feeler stand and the numeral 2 indicates the body of the feeler device and 3 the cap thereof, these parts being adjustably connected with the stand by the bolt 4 which passes through the elongated slot 5 in the parts 2 and 3 and a slot 6 in the stand. The

part 2 has a rectangular recess 7 for receiving a similar shaped enlargement 8 on the cap and screws 9 pass through these parts to hold the cap on the body. A slide 10 fits in a groove 11 in the body and is held in place by the cap and the detector lever 12 is pivoted to the slide, as shown at 13. This detector lever is of the usual construction, but is preferably formed with a fibre end 14 having the toothed extremity 15 for engaging the filling on the bobbin A. The right-angled intermediate portion 16 of the detector has a projection 17 thereon which is engaged by a spring 18 fitting in the aligning grooves 19 in the cap and body, with one end of the spring passing through a bore 20 formed in the enlargement 8 of the cap. A set screw 21 closes the end of this bore and acts as adjusting means for the spring. The tail of the detector is formed with a notch 22 for receiving a stop pin 23 on the slide and the extremity of the tail is curved outwardly and has a threaded hole therein to receive a set screw 24 which is held in adjusted position by the nut 25.

The forward end of the slide is bent upwardly at right angles, as shown at 26, and this end has a threaded hole therein to receive a set screw 27 which carries a cross piece 28 at its inner end, this cross piece being adapted to be engaged by the arm 29 formed on the transerrer lever of the machine. The purpose of this construction is to move the slide forwardly whenever the transerrer arm has a transferring movement.

Thus it will be seen that as long as the bobbin A contains thread or yarn, the detector 12 and the slide 10 will simply be moved by the movement of the lay without rocking the detector lever on its pivot, due to the relation between the intermediate part 6 of the lever, the pivot 13 and the spring 18, but when the bobbin is empty, the teeth 15 of the lever, engaging the empty bobbin, will cause the lever to rock on its pivot so that the adjustable member 24 on the tail of the lever will be pressed against the hook 30 and cause said hook to engage the hook 31 and thus cause the abrasive action. During this rocking movement of the lever 12, the slide 10

does not move so that the cross piece 28 on the screw 27 will be engaged by the arm 29 of the transerrer lever and thus the feeler mechanism will be withdrawn from the path 6 of the incoming bobbin.

It is thought from the foregoing description that the advantages and novel features of the invention will be readily apparent.

It is to be understood that changes may 10 be made in the construction and in the combination and arrangement of the several parts, provided that such changes fall within the scope of the appended claims.

What I claim is:—

- 15 1. In a loom, including a stand, the transfer hooks and the arm on the transerrer lever, a slide on the stand, a detector lever pivoted to the slide, spring means for holding one end of the lever against the yarn on 20 the bobbin, a part on the tail of the lever for moving one hook into engagement with the other when the lever is moved by an empty bobbin and a part on the slide engaged by 25 the arm on the transerrer lever for moving the slide and lever out of the path of the incoming bobbin.
2. In a loom, including a stand, the transfer hooks and the arm on the transerrer lever, a slide on the stand, a detector lever 30 pivoted to the slide, spring means for holding one end of the lever against the yarn on the bobbin, a part on the tail of the lever for moving one hook into engagement with the other when the lever is moved by an empty 35 bobbin and a part on the slide engaged by the arm on the transerrer lever for moving the slide and lever out of the path of the incoming bobbin, said part on the tail of the lever being adjustable and the arm engaging 40 part on the slide being adjustable.
3. In a loom, including a stand, the transfer hooks and the arm on the transerrer lever, a slide on the stand, a detector lever pivoted to the slide, spring means for holding 45 one end of the lever against the yarn on the bobbin, a part on the tail of the level for moving one hook into engagement with the other when the lever is moved by an empty bobbin and a part on the slide engaged by 50 the arm on the transerrer lever for moving the slide and lever out of the path of the incoming bobbin, said part on the tail of the lever being adjustable and the arm engaging part on the slide being adjustable, and 55 the bobbin engaging end of the feeler lever having teeth thereon.

In testimony whereof I affix my signature.

FRANK F. SCHMANSKA.
